UNITED STATES PATENT OFFICE.

SAMUEL D. BLACKBURN, OF LANSDALE, PENNSYLVANIA.

STOVE.

1,219,229.

Specification of Letters Patent.

Patented Mar. 13, 1917.

Application filed October 12, 1915. Serial No. 55,522.

To all whom it may concern:

Be it known that I, SAMUEL D. BLACKBURN, a citizen of the United States, residing at Lansdale, in the county of Montgomery and State of Pennsylvania, have invented certain new and useful Improvements in Stoves; and I do hereby declare the following to be a full, clear, and exact description of the invention, such as will enable others skilled in the art to which it appertains to make and use the same.

This invention relates to stoves, and has for its primary object to generally improve and render more efficient water heating pipes of stoves.

With this and other objects in view, the invention consists in the novel construction, arrangement and formation of parts as will be hereinafter specifically described, claimed and illustrated in the accompanying drawings, in which:

Figure 1 represents a side elevation of the improved stove,

Fig. 2 represents a vertical central sectional view therethrough, partly in side elevation,

Fig. 3 represents a transverse sectional view on the line 3—3 of Fig. 2,

Fig. 4 represents a top plan view of the grate, and support therefor removed,

Fig. 5 represents a transverse sectional view through the support removed, and

Fig. 6 represents a side elevation of the grate removed from the support, partly in section.

Referring to the drawings in detail, wherein similar reference numerals designate corresponding parts throughout the several views, the numeral 5 indicates the cylindrical body of the stove under which is arranged the ash pit 6. A fuel magazine 7 is supported in concentrically spaced relation to the upper open end of the cylindrical body 5 by a plurality of spacing elements or arms 8. The upper extremity of the magazine 7 is enlarged, as at 9, and provided with a removable cover 10, and the lower end thereof terminates in spaced relation above a rotatable brace 11 supported upon an annular supporting member 12, having a plurality of depending lugs 13 engaged in straps or loops 14 secured to the inner surface of the cylindrical body 5. The brace 11 includes a depending shaft 15, a plurality of radiating brace bars 16 and a handle 17 secured to the lower extremity of

the shaft 15 and projecting through a slot formed in the lower portion of the cylindrical body 5, whereby the brace 11 may be oscillated. The annular brace supporting member or frame 12 is provided with a plurality of integral U-shaped members 18 of less width than the space between the radiating brace bars 16 and of less length than the latter and adapted to coöperate therewith in supporting the fire.

A casing 19 is supported in concentrically spaced relation to the cylindrical body 5 and the top 20 thereof is spaced from the upper edge of the body to provide a passage 21 for the products of combustion from the fire pit 22. The products of combustion are exhausted from the interior of the casing 19 by a flue 23.

The portion of the cylindrical body 5 disposed within the casing 19 constitutes the inner wall of an annular drum or water chamber 24, the upper extremity of which is disposed in spaced relation to the top 20 of the casing, and the lower end thereof is supported upon the bottom of the latter. An outer water chamber 25 of annular formation is arranged within the casing 19 in spaced relation to the side wall of the latter and the inner chamber 24. The outer drum or chamber 25 is engaged with the top 20 of the casing and the lower end is disposed in spaced relation to the bottom of the casing to provide a passage 26 for the products of combustion, and the drums are connected by water pipes 27. A water supply pipe 28 is connected with the lower extremity of the outer drum 27 and a feed pipe 29 is connected with the upper extremity thereof.

In use, the fire is supported upon the grate 11 and the heated products of combustion resulting from the combustion of fuel in the fire pit 22 are directed upwardly between the magazine 7 and body 5, downwardly between the inner and outer water chambers 24 and 25, respectively, thence upwardly and out through the flue 23, thus quickly heating the water standing in the chambers 24 and 25. Fuel is introduced into the fire pit 22 through the magazine 7.

What I claim is:

1. A stove comprising a body having its upper portion bent outwardly and downwardly upon itself forming a water receptacle, a casing supported by the lower portion of said body and inclosing said water receptacle, and engaging the lower portion

receptacle and positioned above the
e of said receptacle, a plurality of
necting said inner and outer re-
and supporting said outer recep-
external flange positioned on said
n the water receptacle, a spider se-
he inner surface of said body ad-
top portion thereof, a casing in-
e open end of said body and said 30
ptacle and spaced therefrom, said
ting on said flange and the top of
water receptacle, and a magazine
in said body and resting on said

thereof, said casing having a central open-
ing in the top portion thereof, an outer
water receptacle positioned in said casing in
concentric relation thereto, the top portion
5 of said outer water receptacle engaging said
casing forming an additional support there-
for, a plurality of pipes connecting the
water receptacle and forming a support for
said outer water receptacle, a magazine po-
10 sitioned in said central opening in said cas-
ing and extending into said body, and a
grate supported by said body below said
magazine.

2. A stove including a body having an
15 open upper end, the top portion of said body
being bent outwardly and bent at right
angles and then downwardly parallel to said
body and then inwardly in contact with the
lower portion of said body forming a water
20 receptacle, an outer annular water receptacle
arranged in concentric relation to said inner

water rec-
lower edg-
pipes con-
ceptacles :
tacle, an e-
